United States Patent Office

Des. 196,692
Patented Oct. 22, 1963

196,692

PRESSURE REGULATOR

Richard S. Brumm, Oakland, Calif., assignor to Grove
Valve and Regulator Company, Oakland, Calif., a cor-
poration of California

Filed Mar. 27, 1962, Ser. No. 69,453

Term of patent 14 years

(Cl. D78—1)

FIG. 2

FIG. 3

FIG. 4

FIG. 1

FIGURE 1 is a perspective view of a pressure regulator, showing my new design;

FIGURE 2 is a side elevational view thereof, the op-
posite side being substantially the same;

FIGURE 3 is a front elevational view thereof; and
FIGURE 4 is a rear elevational view thereof.

The drawing is shaded to indicate contrasting areas.
I claim:

The ornamental design for a pressure regulator, sub-
stantially as shown and described.
